Primary Examiner — Sandra Morris(74) *Attorney, Agent, or Firm* — John V. Daniluck; Bingham Greenebaum Doll LLP**CLAIM**

The ornamental design for a bottle, as shown and described.

DESCRIPTION

FIG. 1 is a top, front, right side perspective view of a bottle showing my new design, with windows on the rounded shoulder portion of the bottle being transparent, the broken lines forming no part of the claimed design;

FIG. 2 is a left side elevational view of the bottle of FIG. 1, the right side elevational view being identical;

FIG. 3 is a rear elevational view of the bottle of FIG. 1, the front elevational view being identical; and

FIG. 4 is a top plan view of the bottle of FIG. 1.

FIG. 5 is a top, front, right side perspective view of a bottle showing my new design, with windows on the rounded shoulder portion of the bottle not being transparent, the broken lines forming no part of the claimed design;

FIG. 6 is a left side elevational view of the bottle of FIG. 1, the right side elevational view being identical;

FIG. 7 is a rear elevational view of the bottle of FIG. 1, the front elevational view being identical; and,

FIG. 8 is a top plan view of the bottle of FIG. 1.

1 Claim, 8 Drawing Sheets(56)
